[57] CLAIM

The ornamental design for a housing for a bench top band saw, substantially as shown and described.

DESCRIPTION

FIG. 1 is a perspective view of the housing for a bench top band saw of my design showing the top, front and one side thereof;

FIG. 2 is a side elevation view thereof;

FIG. 3 is a front elevation view thereof;

FIG. 4 is a rear elevation view thereof;

FIG. 5 is a top plan view thereof; and

FIG. 6 is a bottom plan view thereof.

FIG. 1FIG. 3*FIG. 2*FIG. 4

FIG. 6
